United States Patent Office.

THOMAS A. SEARLE, OF PROVIDENCE, RHODE ISLAND.

Letters Patent No. 77,107, dated April 21, 1868.

IMPROVEMENT IN WRENCHES.

The Schedule referred to in these Letters Patent and making part of the same.

TO ALL WHOM IT MAY CONCERN:

Be it known that I, THOMAS A. SEARLE, of Providence, in the county of Providence, and State of Rhode Island, have invented a new and improved Wrench; and I do hereby declare that the following is a full, clear, and exact description thereof, which will enable others skilled in the art to make and use the same, reference being had to the accompanying drawings, forming part of this specification.

This invention relates to a new and improved method of constructing wrenches for turning nuts and screw-bolts, whereby the same are more simple in their construction, and whereby, also, the same are more certain and reliable in their action, and are more readily adjusted to nuts and screw-bolt heads of different sizes.

It consists of a segment of a geared pinion, attached to the shank working in a geared rack on a part of one of the jaws of the wrench, whereby, by the bending of the jaws in one direction, the jaws of the wrench are closed upon a nut or other object between said jaws; it consists also of a loose collar on the shank of the wrench, forced against the jaws, thereby holding said jaws in any required position with respect to the handle of the wrench. In the accompanying plate of drawings—

Figure 1 is a vertical sectional view of my invention, taken in the line $y y$, fig. 2.

Figure 2 is a detail vertical section of the same, taken in the line $x x$, fig. 1.

Similar letters of reference indicate corresponding parts.

A is the fixed jaw of the wrench. a is the movable jaw. a' is a pin in jaw A, on which the movable jaw a moves. a^2 is a pivot on which jaw A turns. H' is the shank of the wrench. B is a fixed pinion on the end of the shank of the wrench. D is a movable collar on the shank H'. S is a spring. H is the handle. n is a nut which secures the shank H' to the handle H.

The shank H' is of the same general form, and is made of the same material as the shank of monkey-wrenches now in common use, and is secured to the handle H by the nut n . Said shank H' has upon the upper end of the same, either a part thereof, or rigidly secured thereto, the segment of a spur-gear pinion, B, to which is pivoted, by a strong pivot, a^2 , the jaw A, so as to permit to the jaws of the wrench a slight sidewise motion, in the arc of a circle whose centre is the pivot a^2 . The jaw A, in respect to the opposite jaw, a , is a fixed jaw, having no other motion than around the pivot a^2 .

Said jaw A is provided, on the inside, with a groove or slot, to receive the arm of the movable jaw a . The movable jaw a has an arm at right angles to itself, extending towards the jaw A, said arm being either a part of the said jaw a , or rigidly attached thereto, said arm being fitted so as to slide in the slot in the jaw A, so that the jaw a may approach nearer to or be moved further from the fixed jaw A. Said arm of the jaw a is provided on the under side with teeth, so as to form a rack, said teeth engaging with the teeth on the segment B. Said arm of the jaw a has a slot through the same, so that it will slide freely over a strong pin, a' , attached to the jaw A, so that by turning the jaw A to the right, upon the pivot a^2 , as shown, the teeth on the segment B will force the jaw a , through the teeth on the arm of said jaw a , towards the jaw A, or close the jaws of the wrench by the reverse operation, moving the said jaw a from the jaw A, thereby opening the jaws of the wrench. Upon the shank H' is a loose collar, D, the upper end of the same resting against the lower part of the jaw A, said collar D being held against said jaw a by a spiral spring, S, or its equivalent, resting on a flange on the lower end of the collar D, and against the handle H, as shown, the object of which is to prevent the jaws of the wrench from turning on the pivot a^2 when not moved by the hand, and to keep the same in a vertical position, as shown, when not in use.

The operation is readily seen from the above description, and from the drawing, the jaws A and a being closed or opened by turning the said jaws on the pivot a^2 . It may be constructed of malleable iron or wrought iron, or of malleable and wrought iron combined, hardened, so as not to bend or wear the handle, being made of wood.

Constructed as above described, it constitutes a cheap and reliable wrench for turning nuts or bolts, the

advantages of which are that it holds the nut or bolt-head more firmly, and is more easily adjusted to bolt-heads and nuts of different sizes than the wrenches now commonly in use.

I claim as new, and desire to secure by Letters Patent—

The sliding collar D and spring S, in combination with the handle H, shank H', toothed segment B, stationary jaw A, slotted movable jaw a, and pivots a¹ a², all constructed, arranged, and operating as and for the purpose described.

THOMAS A. SEARLE.
